UNITED STATES PATENT OFFICE.

SAMUEL H. SOLS, OF HOUSTON, TEXAS.

DESIGN FOR A BURIAL-CASKET.

56,483.

Specification for Design.

Patented Oct. 26, 1920.

Application filed May 11, 1920. Serial No. 380,671. Term of patent 7 years.

To all whom it may concern:

Be it known that I, SAMUEL H. SOLS, a citizen of the United States, residing at Houston, in the county of Harris, State of Texas, have invented a new, original, and ornamental Design for a Burial-Casket, of which the following is a specification, reference being had to the accompanying drawing, forming part thereof.

Figure 1 shows a perspective view of the casket showing my new design, and

Fig. 2 shows a transverse, sectional view.

I claim—

The ornamental design for a burial casket as shown.

SAMUEL H. SOLS.
